TIMOTHY WHITBY, OF YORK ROAD, LAMBETH, ENGLAND.

Letters Patent No. 68,474, dated September 3, 1867; patented in England August 29, 1866.

IMPROVED ARMOR FOR SHIPS-OF-WAR.

The Schedule referred to in these Letters Patent and making part of the same.

TO ALL TO WHOM IT MAY CONCERN:

Be it known that I, TIMOTHY WHITBY, of York Road, Lambeth, in the county of Surrey, England, a subject of the Queen of Great Britain, have invented or discovered new and useful "Improvements in Constructing Vessels-of-War and other structures required to be rendered shot-proof;" and I, the said TIMOTHY WHITBY, do hereby declare the nature of the said invention, and in what manner the same is to be performed, to be particularly described and ascertained in and by the following statement thereof; that is to say—

In constructing vessels-of-war according to this invention, I attach armor plates to the exterior of those parts of the outer skin of the vessel that are required to be rendered shot-proof, and outside the armor plating I attach metal plates formed into loops, or otherwise formed to present inclined or curved surfaces to projectiles, in order that the projectiles may be deflected by these surfaces, and so turned out of their course before striking against the armor plating. The projectiles will thus be prevented from striking fairly against the armor plating, and therefore the armor plating will be better able to offer resistance to them. The curved plates are by preference of steel, in order that when struck by a projectile they may act as springs and take away from the velocity of the projectile. A thin skin or plating is placed outside the curved or angular plates, to enclose them water-tight and form the exterior of the vessel. If desired, armor plating may be dispensed with, and the curved or other plates be alone employed to protect the outer skin of the vessel. The curved or angular plates are by preference secured in such a manner that they can readily be removed and replaced. If desired, two sets of curved plates may be employed, one exterior of the other.

Batteries, forts, and other structures desired to be rendered shot-proof may be protected in a similar manner to that above described. Curved metal plates may also be employed as a means of retaining cylindrical or other forms of chill-cast metal on the exterior of those parts of a ship that are to be rendered shot-proof, the hollows formed by the bends or curves in the metal plates being filled up by the chill-cast metal pieces, or chill-cast metal pieces may be otherwise enclosed or retained within a casing or plating of wrought metal on the exterior of a ship or vessel.

Having thus stated the nature of my invention, I will proceed to describe more fully the manner of performing the same

Description of the Drawings.

Figure 1 shows a horizontal section,

Figure 2 a vertical section, and

Figure 3 a side view partly in section of a portion of the side of an iron ship or vessel protected with armor plating and deflecting surfaces on the exterior thereof.

The deflecting surfaces shown in these figures are of chill-cast metal, but other forms of deflecting surface may be employed, such as curved plates of wrought metal, or plates of metal otherwise formed to present inclined or curved surfaces to projectiles may be applied exterior of the armor plating. The deflecting surfaces are enclosed within a skin or casing, as above described. The chill-cast deflecting surfaces *a a* shown in figs. 1, 2, and 3, are composed of a series of chill-castings similar to chill-cast projectiles such as are now commonly manufactured for firing from ordnance. These castings are connected one to another by short wrought-iron pieces *b*, similar to short lengths of the ordinary double-headed railway rail. These pieces are placed in the moulds in which the pieces *a* are to be cast, and the pieces *a* are cast upon them in such manner as to form a kind of chain, in the manner represented in the drawing. A series of chains so formed is placed side by side over the exterior of the armor plating *c* of the vessel, and the chains are enclosed within a skin or casing, *e*, of iron, which forms an even surface and water-tight casing for the outer surface of the vessel. The chains are also held by means of the bolts *d*, as shown. In the drawing I have shown the sides of the vessel to which the armor plating is affixed to be composed of two parallel skins, *ff*, of iron plating, connected at intervals the one to the other, but other forms or constructions of vessels may be similarly protected with deflecting surfaces on the exterior of armor plating.

Figure 4 is a vertical section, and

Figure 5 a side view partly in section of a portion of the side of a vessel having no armor plating, but having deflecting surfaces applied to its exterior to protect it from shot, a skin or plating being according to

my invention placed on the exterior of the deflecting surfaces, to enclose them and form the exterior of the vessel, as before described. The deflecting surfaces are composed of curved plates *a* secured to the sides of the vessel by bolts *b*, but other forms of deflecting surface may be employed, and exterior of these deflecting surfaces is the skin or plating *c*, to form an even surface on the exterior of the vessel. The spaces between the plates are shown to be filled in with chill-cast blocks of metal similar to chill-cast projectiles such as are now commonly employed for firing from ordnance.

Figure 6 is a vertical section, and

Figure 7 a side view partly in section of a portion of the side of a vessel protected by other forms of deflecting surfaces. The deflecting surfaces in this arrangement are composed of curved or looped metal plating *a*, secured to the sides of the vessel by bolts *b*, as shown. Exterior of these deflecting surfaces is the skin or plating *c*, to form an even surface to the exterior of the vessel. The interstices between the bends or loops of the deflecting plates may, as in the arrangement shown in figs. 4 and 5, be filled in with chill-cast blocks *d*.

Having thus described the nature of my invention, and the manner of performing the same, I would have it understood that what I claim, is—

The protecting those parts of vessels and other structures that are required to be rendered shot-proof, by the combination of an exterior casing of chill-cast metal blocks and wrought plating, the plating being employed to enclose and retain the chill-cast pieces, as herein described.

TIMOTHY WHITBY.
